UNITED STATES PATENT OFFICE.

GEORGE H. ANGELL AND CHARLES L. LESLIE, OF OMAHA, NEBRASKA.

SEAL-LOCK.

SPECIFICATION forming part of Letters Patent No. 334,407, dated January 19, 1886.

Application filed October 1, 1885. Serial No. 178,700. (Model.)

To all whom it may concern:

Be it known that we, GEORGE H. ANGELL and CHARLES L. LESLIE, citizens of the United States, residing at Omaha, in the county of Douglas and State of Nebraska, have invented 5 certain new and useful Improvements in Seal-Locks, of which the following is a specification, reference being had therein to the accompanying drawings.

10 Our invention relates to improvements in car-sealing or seal-fastening devices by which said fastening cannot be opened without indicating the same to have been done.

15 Our improvement consists in the mechanism illustrated in the accompanying drawings, in which—

Figure 1 is a face view of a seal-lock constructed in accordance with our invention; Fig. 2, a vertical section of the same; Fig. 3, 20 a side view of the same; Fig. 4, a rear view of the face-plate; Fig. 5, a horizontal section of the lock; Fig. 6, a top view of said lock. Figs. 7 and 8 are front views of sealing-cards used with the lock. Fig. 9 is a front perspective view of the lower portion of the back plate of the lock. Fig. 10 is a horizontal section of the front and back plates and sealing-card on line $x x$ of Fig. 2. Fig. 11 is a perspective view of a knife-plate carrying two blades. 25 Fig. 12 is a front view of a slightly modified form of our lock, in which the knife projects from the rear of the sliding front plate. Fig. 13 is a side view of the same. Fig. 14 is a top view of the same.

30 The back plate, A', of the lock has generally projecting from its upper end an arm, A, bent in the form of a hook, having its free end extending forward of the back plate and entering a socket, B, formed for its reception in the upper front portion of the face-plate F. From the lower portion of said face-plate projects a lug, C, by which the face-plate can be drawn downward to withdraw the end of the hook from its socket and open the lock.

40 From the rear of the back plate projects a perforated lug, D, to retain one end of a chain to fasten the lock to a car.

The back plate, A', has its vertical edges provided with grooves A² to receive the edges of 50 the front plate and permit the latter to slide for a limited distance in said grooves, said distance being sufficient to permit the sealing-

card E to be placed in position when the front plate is open to its extreme lower limit.

From the lower portion of the back plate, 55 A', projects toward the front the knife H, having its edge upward, against which the sealing-card rests when the seal is closed. This knife can be either rigidly secured to the back plate, in which case the sealing-card has to be 60 slightly sprung or bent vertically to insert it past the knife into the lock, or the knife or knife-blades can be mounted on a spring or secured to a thin steel plate, h, retained by screws passing through slots that permit it to 65 spring back against the back plate while entering the sealing-card into the lock. This arrangement may be reversed, and the seat for the card and the knifeway may be in the back plate, as shown in Figs. 12 and 13, and 70 the knife H² be secured to the rear of the face-plate to rest upon the top edge of the sealing-card and cut the latter vertically in two from top to bottom before the lock can be opened.

For the passage of the knife H, attached to 75 the back plate, a vertical groove or knifeway, I, is formed in the back of the front plate. This plate is also provided with a rectangular recess, F², to retain in position the glass or transparent covering G of the seal, and a larger 80 but less deep recess, F³, to receive the sealing-card E. The sealing-card may be composed of paper, card-board, wood, lead, or of sheet metal—as tin, brass, copper, &c.—and made of such width, length, and thickness as will 85 fit snugly in the receptacle F³ provided for it in the lock, and be cut or torn in two or more separate parts while forced against the edge of the knives. The sealing-card may be made with a portion punched out near its lower 90 edge, as shown at e in Fig. 7, through which the knife H enters in position to cut or tear through the balance of the card, leaving a margin below to hold the parts of the card together. The sealing-card bears printed or 95 stamped inscriptions and numbers, from which it can be recognized. There is an opening, F⁴, in the face-plate, through which and its glass G the sealing-card can be seen, and any tampering with the lock be discovered. 100

We are aware that seal-locks have been formed with a hollow body carrying therein a pivoted knife, and a shackle passing through said body and having a recess for the recep-

tion of a card adapted to bear against the edge of the knife, and do not claim this construction. Neither do we claim a seal-lock provided with a bolt carrying a knife at its outer end in connection with a casing containing a card to be split by said knife in opening the lock.

Having now fully described our invention, what we claim, and desire to secure by Letters 10 Patent, is—

A seal-lock consisting of two plates of metal, the front one of which is adapted to slide vertically in grooves within the back plate and is provided with a projecting lug on the front

and a knifeway in the rear, in combination 15 with a knife projecting from the lower portion of the back plate, and a card inserted under the bottom edge of the front plate and sprung in front and above the knife, substantially as and for the purpose described. 20

In testimony whereof we affix our signatures in presence of two witnesses.

GEORGE H. ANGELL.
CHARLES L. LESLIE.
